MECHANICAL RIDING TOY

Gustavo Vazquez Glumer, Mexico City, Mexico
Application March 20, 1958, Serial No. 722,798

4 Claims. (Cl. 280—1.183)

The present invention relates to mechanical riding toys, and particularly to a simulated horse having legs moved by the shifting weight of the rider.

The primary object of the invention is to provide a mechanical riding toy having movable wheeled legs in which the wheels are steerable and have brakes to prevent movement in a reverse direction.

Another object of the invention is to provide a mechanical riding toy of the class described above wherein the front and rear legs are operated simultaneously in opposite directions.

A further object of the invention is to provide a mechanical riding toy of the class described above having a steering mechanism controllable by reins extending from a simulated horse head.

A still further object of the invention is to provide a simulated horse type mechanical riding toy wherein the toy driving mechanism is locked during the mounting of the toy by the rider.

Another object of the invention is to provide a mechanical riding toy of the class described above which is inexpensive to manufacture, simple to operate, and which will be long lasting in rough service.

Other objects and advantages will become apparent in the following specification when considered in the light of the attached drawings, in which:

Figure 1 is a side elevation of the invention with the body and frame of the horse shown in broken lines.

Figure 2 is a fragmentary perspective view of the operating mechanism of the horse illustrated in Figure 1.

Figure 3 is a semi-diagrammatic top plan view of the steering linkage shown in straight line position.

Figure 4 is a view similar to Figure 3 showing the wheels steered for a right turn.

Figure 5 is a view similar to Figure 3 showing the braking position of the wheels when both reins are pulled.

Figure 6 is an enlarged fragmentary vertical cross-section taken along the line 6—6 of Figure 1, looking in the direction of the arrows.

Figure 7 is a fragmentary perspective view of the lock mechanism.

Figure 8 is an enlarged side elevation of one of the wheels showing the braking structure.

Figure 9 is a fragmentary horizontal section taken along the line 9—9 of Figure 8, looking in the direction of the arrows.

Figure 10 is a perspective view similar to Figure 2, illustrating a modified form of the invention.

Referring now to the drawings in detail wherein like reference characters indicate like parts throughout the several figures, the reference numeral 20 indicates generally a mechanical riding toy constructed in accordance with the invention.

The toy 20 comprises a hollow horse simulating body 21, shown in dotted lines in Figure 1, and having a head 22, a saddle 23, depending front legs 24 and depending rear legs 25. The body 21 has a rigid frame 26 mounted therein to support the operating mechanism thereof.

2

The front legs 24 are mounted respectively on vertical tubular frame members 27, 28 which are arranged in parallel relation and secured together adjacent the upper ends thereof by a transverse bar 29 rigidly secured to the frame members 27, 28 at its opposite ends, and a second transverse bar 30 arranged parallel to the bar 29 with its opposite ends secured respectively to ears 31, 32 secured to the upper ends of the frame member 27, 28 and extending forwardly therefrom.

10 The bar 30 is journaled in the frame 26 to provide the frame members 27, 28 with a swinging movement about a transverse horizontal pivot.

A shaft 33 is telescopically mounted in the frame member 27 projecting above and below the upper and lower ends thereof. A fork 34 is rigidly secured to the lower end of the shaft 33 and has a ground engaging wheel 35 journaled therein on an axle 36.

The fork 34 is provided at its lower rear extremity on one side with an integral downwardly and rearwardly sloping channel way 37 in which is supported a steel ball 38 for engagement with the inner surface of the rim 39 of the wheel 35.

As can be best seen in Figures 8 and 9, the wheel 35 on rotating in a counter clockwise direction, as viewed in Figure 8, will cause the ball 38 to rise in the trackway 37 and the wheel 35 can freely rotate. When the wheel 35 is rotated in a reverse direction, the ball 38 is jammed between the rim 39 and the trackway 37 locking the wheel 35 against further clockwise rotation. The effect of the ball 38 and trackway 37 is to produce a wheel 35 capable of rotating in a counterclockwise direction only.

The upper end of the shaft 33 is provided with a forwardly extending horizontal arm 40 fixed to the shaft 33 so as to rotate therewith. A coil spring 41 encompasses the shaft 33 and engages the arm 40 to normally bias the arm 40 in a counterclockwise direction, as viewed in Figure 3.

40 A shaft 42 is journaled in the frame member 28 and is identical to the shaft 33. The shaft 42 has a fork 34 and wheel 35 fixed to its lower end in the same manner as the fork 34 and wheel 35 are fixed to the shaft 33.

An arm 43 is fixedly secured to the upper end of the shaft 42 in horizontal forwardly extending relation parallel to the arm 40, and a spring 44 encompasses the upper end of the shaft 42 and engages against the arm 43 to normally bias the arm 43 in a clockwise direction, as viewed in Figure 3.

45 A tie rod 45 extends horizontally parallel to the bar 30 and has its opposite ends connected by pivots 46, 47 respectively, to the forward ends of the arms 40, 43 connecting the arms 40, 43 together for simultaneous rotary movement. The tie rod 45 has a depending stud 48 fixed thereto intermediate the opposite ends thereof.

50 A vertical shaft 49 is fixed to the frame 26 and has a transversely extending steering bar 50 journaled thereon. A spring 51 is fixed to the shaft 49 with its opposite ends engaging the steering bar 50 normally biasing the bar 50 into a position perpendicular to the longitudinal center line of the toy 20. The opposite ends of the bar 50 are provided with integral ears 52, 53 extending upwardly therefrom.

55 A yoke 54 extends rearwardly from the steering bar 50 and is integrally formed therewith. The yoke 54 engages on opposite sides of the stud 48 and has the rear end portions thereof downwardly curved at 55.

60 The rear legs 25 of the toy 20 are mounted on vertically extending tubular frame members 56, 57 which are secured together by a transverse cross bar 58 extending horizontally therebetween adjacent to but spaced from the upper ends thereof. A second cross bar 59 is arranged parallel to the cross bar 58 and extends between ears 60, 61 secured integrally to the upper ends of the frame

members 56, 57. The ears 60, 61 extend rearwardly from the frame members 56, 57 in parallel relation. The transverse bar 59 is journalled in the frame 26 parallel to the cross bar 30 to support the frame members 56, 57 for swinging movement about a horizontal pivot.

A shaft 62 is journalled in the frame member 56, and is provided with a fork 34 fixed to its lower end supporting a wheel 35. The fork 34 and wheel 35 fixed to the shaft 62 are identical to the fork 34 and wheel 35 fixed to the shaft 33. An arm 63 is fixed to the upper end of the shaft 62 and extends forwardly therefrom.

A shaft 64 is journalled in the frame member 57 and has a fork 34 fixed to its lower end supporting a wheel 35 of identical construction to the fork 34 and wheel 35 fixed to the shaft 33. An arm 65 is fixed to the upper end of the shaft 64 and extends forwardly therefrom in horizontal relation.

A shaft 66 is fixed to the frame 26 in vertically extending position and has a pair of bell crank levers, generally indicated at 67 and 68, journalled thereon for pivotal movement in a horizontal plane. The bell crank lever 67 has a transverse arm 69 and a longitudinal arm 70 integrally secured to gether.

A depending flange 71 is integrally formed on the forward edge of the arm 69 and provided with a horizontal slot 72. A depending ear 73 is integrally formed on the forward end of the longitudinal arm 70, as best shown in Figure 2.

The bell crank lever 68 has a transverse arm 74 and a longitudinally extending arm 75 integrally formed therewith. A depending flange 76 is formed on the forward edge of the transverse arm 74 and provided with a horizontal slot 77, similar to the slot 72 in the flange 71.

The forward end of the longitudinal arm 75 is provided with an integral upstanding ear 78, and a spring 65' fixed to the shaft 66 has its opposite ends engaging the transverse arms 69, 74 to normally bias the arms 69, 74 in a rearward direction.

The transverse arm 69 at the end thereof opposite the shaft 66 is provided with a rearwardly extending member 79, and the transverse arm 74 has integrally formed thereon at the end thereof opposite the shaft 66 a rearwardly extending member 80 arranged normally parallel to the member 79. A coil spring 81 has the opposite ends thereof connected to the rear ends of the members 79, 80 to normally bias the members 79, 80 together.

A rod 82 extends through the slot 72 and has a head 83 formed on the rear end thereof. The forward end of the rod 82 is provided with a hook 84 extending through the ear 52 on the steering bar 50. A rod 85 extends through the slot 77 and has a head 86 formed on the rear end thereof. The forward end of the rod 85 is provided with a hook 87 which engages the ear 53 on the opposite end of the steering bar 50.

A U-shaped guide member 88 is fixedly secured to the frame 26 and has a pair of spaced parallel depending guide bars 89, 90 integrally formed thereon. An elongated arcuate cam bar 91 is fixedly secured at its forward end to the bar 30 intermediate the opposite ends thereof at 92. The forward end portion of the cam bar 91 is provided with a depending portion 93 fixedly secured at 94 to the bar 29 intermediate the opposite ends thereof.

The cam bar 91 functions as a lever to pivot the frame members 27, 28 with their transverse bar 30 in the frame 26. The cam bar 91 engages between the guide bars 89, 90 and is guided for movement in a vertical plane therebetween.

An elongated arcuate cam bar 95 has the rear end thereof fixedly secured at 96 to the center of the transverse bar 59 and is provided with a depending portion 97 fixedly secured at 98 to the transverse bar 59. The cam bar 95 functions as a lever to swing the frame members 56, 57 and their transverse connecting bar 59 in the frame 26. The cam bar 95 in the forward end portion thereof engages between the guide bars 89, 90 and is

maintained for swinging movement in a vertical plane thereby.

A stirrup support lever 99 is journalled on the forward end 100 of the cam bar 95 for swinging movement in a vertical plane, and the cam bar 95 is provided with a pair of oppositely disposed integral forwardly extending stop members 101, 102 arranged to engage beneath the opposite lower edges of the stirrup support 99. The stop member 102 is positioned substantially below the stop member 101, for reasons to be assigned. A spring 103 is fixed to the forward end 100 of the cam bar 95 and has one end thereof engaging the stirrup support 99 to normally bias the support 99 into engagement with the stop 101.

The stirrup support 99 has an integral ear 104 formed on one end thereof, and a second integral ear 105 formed on the opposite end thereof. A right side stirrup strap 106 is suspended from the ear 104 by means of a buckle 107, and a left side stirrup strap 108 is suspended from the ear 105 by a buckle 109.

A hook 110 is formed integrally with the center of the stirrup support 99 extending upwardly therefrom and opening toward the ear 105. A hook 111 is fixedly secured to the frame 26 and positioned to cooperatively engage with the hook 110 with the stirrup support 99 pivoted on the end 100 of the cam bar 95 to a position with the ear 105 lowermost.

The stirrup straps 106, 108 are each provided with a stirrup 112 secured to the lower end thereof.

A pair of spaced apart parallel brackets 113, 114 are secured to the cam bar 95 and provided with depending spaced apart parallel guide portions 115, 116 engaged on opposite sides of the cam bar 91. A roller 117 is journalled on a shaft 118 mounted on the brackets 113, 114. The roller 117 engages the upper surface of the cam bar 91, as best seen in Figure 6.

A pair of spaced parallel forwardly extending arms 119, 120 are integrally formed respectively on the brackets 113, 114 intermediate the upper and lower ends thereof and have a roller 121 journalled therebetween on a shaft 122 at the forward ends of the arms 119, 120. The roller 121 engages the upper surface of the cam bar 91 to maintain the cam bars 91, 95 in spaced apart relation.

A coil spring 123 has its forward end secured to the transverse bar 29 and its rear end secured to the frame 26 to normally bias the frame members 27, 28 into an upright position. The spring 123 is provided with one or more turnbuckles 124 by means of which the tension of the spring 123 can be controlled.

The head 22 of the horse 21 is provided with a pair of spaced apart parallel separately movable bell crank bridle bit ends 125 having conventional reins 126 secured to the lower ends thereof and a pair of flexible wires 127, 128 connected respectively to the upper ends thereof. The flexible wires 127, 128 extend through guide tubes 129, 130 respectively mounted on the U-shaped guide member 88, as seen in Figure 2. The flexible wire 127 at its rear end is hooked to the outer end of the transverse arm 69 of the bell crank 67, and the flexible wire 128 is hooked to the outer end of the transverse arm 74 of the bell crank 68.

In the use and operation of the invention, the toy 20 is mounted by the rider stepping into the stirrup 112 which causes the stirrup support 99 to pivot with the hook 110 engaging the hook 111 to lock the stirrup lever 99 against further downward movement.

After the rider has mounted the toy 20, he engages both feet in the stirrups 112 so that his weight is equally divided between the stirrup straps 106, 108 and the stirrup support bar 99 returns to a horizontal position. The rider then rises in the stirrups 112 to increase the weight supported by the stirrup support 99 and the cam bar 95 is pressed downwardly so as to simultaneously swing the

frame members 56, 57 rearwardly and to press downwardly by means of the rollers 117, 121 against the cam bar 91 to thus cause the frame members 27, 28 to be swung forwardly against the tension of the spring 123. As the frame members 56, 57 are swung rearwardly, the wheels 35 thereon are locked against rearward movement so that the horse 20 is moved forwardly.

The rider then sits in the saddle 23 removing his weight from the stirrups 112 to permit the spring 123 to pull the frame members 27, 28 to their upright position which will, through engagement of the cam bar 91 with the rollers 121, 117, move the cam bar 95 to bring the frame members 56, 57 to their upright position. The wheels 35 supporting the frame members 27, 28 can not move rearwardly, so the wheels 35 supporting the frame members 56, 57 are drawn forward as the frame members 27, 28, 56, 57 return to their upright positions.

A continuation of the alternate movements of the rider placing his weight first in the stirrups 112 then in the saddle 23 will cause the legs 24, 25 to alternately spread apart and return to upright position with the one-way action of the wheels 35 causing the toy 20 to move forwardly.

The toy 20 is steered by means of the reins 126 operating through the bit ends 125. The bell crank levers 67, 68 are caused to swing on the shaft 66 by the movement of the flexible wires 127, 128 when moved by the reins 126.

The ear 73 on the bell crank lever 67 is coupled to the arm 63 by means of a connecting link 131, and the ear 78 on the bell crank lever 68 is connected to the arm 65 by a link 132. Swinging movement of the bell crank lever 67 caused by the movement of the wire 127, swings the arm 63 inwardly while the arm 65 is swung outwardly by the link 132 and swinging movement of the bell crank lever 68.

The rods 82, 85 connecting the flanges 71, 76 respectively with the ears 52, 53 of the steering bar 50 causes the steering bar 50 to swing on the shaft 49, moving the arm 40 outwardly and the arm 43 inwardly so that the wheels 35 supporting the frame members 27, 28 are steered oppositely of the wheels 35 supporting the frame members 56, 57.

If the reins 126 are pulled simultaneously rearwardly to pull simultaneously forwardly on the flexible wires 127, 128, the bell crank levers 67, 68 will be swung oppositely on the shaft 66 against the tension of the spring 81, and the arms 63, 65 will be swung inwardly simultaneously, as illustrated in Figure 5, so that the wheels 35 supporting the frame members 56, 57 will be both aimed toward the center, thus creating a braking action to retard the forward motion of the toy 20.

The swinging movement of the bell cranks 67, 68 under the direct pull on both of the flexible wires 127, 128, swings the flanges 71, 76 away from the heads 83, 86 on the rods 82, 85 so that the steering bar 50 remains in its transverse position where it is maintained by the spring 51.

Referring now to Figure 10, a modified form of the invention is illustrated wherein tubular frame members 27a, 28a are arranged in spaced parallel relation to form the front leg frames of a toy 20a. The frame members 27a, 28a are connected together by a transverse bar 29a identical to the bar 29, and a second transverse bar 30a parallel thereto and identical to the transverse bar 30.

Ears 31a, 32a are formed integrally on the upper ends respectively of the frame members 27a, 28a and the transverse bar 30a has its opposite ends fixedly secured thereto. A fork 34 identical to the fork 34 of the preferred form of the invention is fixedly secured to the lower end of each of the frame members 27a, 28a with a wheel 35 journalled therein.

A pair of frame members 56a, 57a are arranged in spaced parallel relation to form the rear legs of the toy 20a and are supported at their upper ends by trans-

verse bars 58a, 59a identical to the transverse bars 58, 59 of the preferred form of the invention.

A shaft 62a is journalled in the frame member 56a and has a fork 34 fixed to the lower end thereof with a wheel 35 journalled therein. A bell crank lever 63a is fixedly secured to the upper end of the shaft 62a, for reasons to be assigned. A shaft 64a is journalled in the frame member 57a and has a fork 34 fixedly secured to the lower end thereof carrying a wheel 35 therein. A bell crank lever 65a is fixedly secured to the upper end of the shaft 64a, for reasons to be assigned.

A cam bar 91a identical to the cam bar 91 is fixedly secured to the transverse bars 29a, 30a in the same manner as the cam bar 91 is fixedly secured to the transverse bars 29, 30. A cam bar 95a identical to the cam bar 95 is fixedly secured to the transverse bars 58a, 59a in the same manner as the cam bar 95 is fixedly secured to the transverse bars 58, 59. A coil spring 123a extends between the transverse bar 29a and the transverse bar 58a to normally bias the frame members 27a, 28a and the frame members 56a, 57a into an upright position. The cam bars 91a, 95a are operatively associated in exactly the same manner as the cam bars 91, 95 in the preferred form of the invention and operate in the same manner.

A connector rod 131a is secured to the forwardly extending portion of the bell crank lever 63a and extends transversely therefrom. A connector tube 132a is telescopically engaged over the connector rod 131a and has its opposite end connected to the forward extending portion of the bell crank lever 65a. A coil spring 66a encompasses the rod connector 131a and tubular connector 132a and has its opposite ends fixedly secured to the rod connector 131a and the tubular connector 132a so as to normally bias the bell crank levers 63a, 65a into the position illustrated in Figure 10, with the wheels 35 fixed to the shafts 62a, 64a arranged in parallel relation.

A flexible wire 127a is connected at its forward end to the right hand rein in the same manner as the preferred form of the invention and has its rear end connected to the transverse portion of the bell crank lever 65a. A flexible wire 128a has its forward end connected to the left hand rein in the same manner as the wire 128 is connected in the preferred form of the invention and has its rear end connected to the transverse portion of the bell crank lever 63a.

In the form of the invention illustrated in Figure 10, the toy 20a is mounted and propelled in exactly the same manner as the toy 20, however, the wheels 35 underlying the frame members 56a, 57a at the rear of the toy 20a are alone steered, while the wheels 35 underlying the frame members 27a, 28a at the front of the toy 20a remain in forwardly extending position at all times.

In steering the toy 20a, the flexible wire 128a is moved forwardly by pulling on the left hand rein so that the transverse portion of the bell crank lever 63a is moved forwardly and the wheel 35 supported on the shaft 62a is turned to the right thus steering the toy 20a to the left. The spring 66a swings the bell crank lever 65a to maintain the wheel 35 on the bottom of the shaft 64a in parallel relation to the wheel 35 on the bottom of the shaft 62a. A coil spring 81a is fixed to the frame member 56a and has its opposite ends engaging the bell crank lever 63a to normally maintain the wheels 35 in a straight forward direction.

When it is desired to halt the toy 20a, both of the flexible wires 127a, 128a are pulled forwardly by pulling rearwardly on both of the reins so that the bell crank levers 63a, 65a are swung oppositely against the tension of the spring 66a with the rod 131a sliding in the tubular connector 132a. This movement of the bell crank levers 63a, 65a causes the wheels 35 on the shafts 62a, 64a to be swung outwardly in opposite directions causing a locking action with respect to the floor surface.

It should be understood that numerous structural modi-

ifications and adaptations, in addition to those illustrated, may be resorted to without departing from the scope of the appended claims.

What is claimed is:

1. A mechanical riding toy comprising a simulated horse body, a pair of spaced apart parallel frame members depending from the forward end of said body, transversely extending means pivoting said frame members to said body at their upper end, a wheel journalled on the lower end of each of said frame members, means restricting said wheels to movement in a forward direction of said body, a pair of spaced apart parallel frame members journalled in depending relation on the rear end of said body, a vertical shaft journalled in each of said last named frame members, a wheel journalled on the lower end of each of said shafts, means restricting said last named wheels to movement in a forward direction with respect to said body, a cam lever fixed to said last named frame members and extending forwardly therefrom, a pair of oppositely disposed stirrups suspended from the forward end of said cam lever, a cam bar fixedly secured to said first named frame members and extending rearwardly therefrom underlying said cam lever, antifriction means on said cam lever engaging said

cam bar for moving said cam bar downwardly upon downward movement of said cam lever, hand controlled means for steering the wheels mounted on said shafts, and resilient means in said horse body for biasing said first named frame members to an upright position.

2. A device as claimed in claim 1 wherein guide means fixed to said body engages on opposite sides of said cam lever and said cam bar for maintaining said cam lever and said cam bar in a vertical plane.

3. A device as claimed in claim 1 wherein said first named wheels are mounted on said first named frame members for steering movement about a vertical pivot and means simultaneously operated by said hand controlled means simultaneously steers said front wheels in a direction opposite to that of said rear wheels.

4. A device as claimed in claim 1 wherein the wheels mounted on said shafts may be steered in opposite directions to retard the forward movement of said toy.
